UNITED STATES PATENT OFFICE.

HENRY L. DE ZENG, OF GENEVA, NEW YORK, ASSIGNOR TO DE ZENG STANDARD COMPANY, OF CAMDEN, NEW JERSEY, A CORPORATION OF NEW JERSEY.

DIAGNOSTIC INSTRUMENT.

Application filed March 5, 1925. Serial No. 13,236.

This invention relates to improvements in diagnostic instruments, and has particular reference to the provision of an improved laryngoscope, which is particularly adaptable for use in examining the throat and past the nasal opening.

An important object of the invention is to provide such a device having a source of light and a detachable reflector support.

Another object is to provide such a device with an angularly disposed reflector in the path of light, said reflector being capable of adjustment so as to deflect the light rays to different positions relative to the body portion of the instrument.

Another object is to provide such a device with an adjustable condensing lens, whereby the light may be focused to vary the area of illumination by the instrument.

Another object is to provide such a device wherein the parts may be readily detached for the purpose of sterilization or for interchangeability.

Another object is to provide such an instrument which will be simple in construction, strong and durable in service, and an improvement in the art.

With these and other objects in view, the invention resides in the novel features of construction, combination and arrangement of parts as hereinafter set forth, illustrated in the accompanying drawings, and specifically pointed out in the appended claims.

In the drawings:

Figure 1 is a side elevation of an instrument embodying the invention;

Figure 2 is a fragmentary sectional view of the illuminating head thereof;

Figure 3 is a view similar to Figure 2, illustrating a modified form of construction;

Figure 4 is a detail perspective view of the laryngoscope reflector; and

Figure 5 is a transverse sectional view on the line 5-5 of Figure 3.

In carrying out the invention, a handle member 10, which may be of the battery containing type, or adaptable for connection to an out side source of electrical energy, is fitted with a metallic extention 11 upon its upper end, upon which is operative a nut 12, which is screw threaded and capable of forming an electrical connection between the extention 11 and the upper cap 13 of the handle member 10. The metallic extention 11 is centrally apertured as at 14 and formed

with a reduced threaded extremity 15, to which may be connected the illuminating head designated generally by the reference character 16.

The illuminating head 16 is preferably formed of two angularly disposed members 17 and 18, they being illustrated in the drawings as at right angles to one another, but of course the angle between these two parts may be either acute or obtuse, as is desired. The extension 18 is formed with a smooth cylindrical exterior 19 upon which is slidably and rotatably mounted a sleeve 20 carrying at its forward end a condensing lens 21 of any suitable type. The extremity of the member 18 is further provided with a screw threaded socket 22 for the reception of an incandescent lamp 23; a pair of insulating bushings 24 and 25 are seated in the illuminating head as illustrated, and support the conductor 26 which connects the central terminal from the battery with the central terminal of the lamp butt, thus forming one side of the electrical circuit. The second side of the electrical circuit is formed by the metallic members 11, 12, 17 and 18 by connection with the upper cap 13 of the handle.

Disposed at one side of the sleeve 20 is a boss, 27, having a slightly tapered hole 28, which is adapted to receive a reflector supporting stem 29. The stem 29 carries at its outer end an angularly disposed reflector 30, and is frictionally held in the boss 27.

By virtue of the fact that the sleeve 20 is rotatable on the cylindrical extension 19 of the illuminating head, the reflecting surface of the reflector 30 and its support may be rotated through 360 degrees, thus making it possible to deflect the light rays from the instrument in any direction relative to the axis of the lamp. This is highly desirable because the instrument necessarily has to be used under differing conditions, the patient being examined sometimes lying in bed, and sometimes sitting up in a chair; also by reason of the fact that the sleeve 20 is slidably mounted the light rays may be focused to vary the area of illumination from the instrument.

In its commercial form each instrument will be provided with several stems 29, each with a different size or different type mirror, some having a plain surface and some being concave. In use the proper reflector is selected and attached to the illuminating

head, whereupon it is inserted in the patient's mouth and the sleeve 20 turned to the proper angle so as to illuminate the desired portion of the patient's throat, whereupon the practitioner looks directly over the illuminating head and is able to view the desired parts as reflected in the mirror 30.

In Figure 3, a modified form of the invention is illustrated, wherein the illuminating head 31 is formed with a cylindrical surface 32 and a screw threaded portion 33 upon its extremity. In this form a reflector carrying sleeve 34 is disposed upon the cylindrical extension 32 and held against longitudinal movement by a lens carrying tube 35, which engages the screw threaded portion 33. In this form of the invention the reflector may be rotated about the axis of the lamp but the lens 21 cannot be focused to change the vergence of the light from the instrument.

From the foregoing it will be evident that an improved laryngoscope has been provided wherein the parts may be readily disassembled for the purpose of sterilization and interchanging. The construction is simple

and economical of manufacture, and it is to be understood that changes may be resorted to falling within the scope of the appended claims without departing from the spirit of the invention.

Having thus described my invention, I claim:

1. In combination with the illuminating head of a diagnostic instrument, a light condensing lens, a sleeve carrying said lens and adjustably mounted on the illuminating head, an extension on one side of the sleeve, a reflector support mounted in said extension, and a reflector carried by the support in line with the sleeve.
2. In a device of the character described, a supporting handle, an illuminating head carried by the handle and provided with an angularly disposed extremity, a source of light in the illuminating head, means for varying the vergency of light from the source of light, and an angularly disposed reflector mounted for longitudinal movement with the last mentioned means and rotatable relative thereto.

HENRY L. DE ZENG.
